(57) **CLAIM**

I claim the ornamental design for an ice climbing practice tool, as shown and described.

DESCRIPTION

FIG. 1 is a lower rear perspective view of the ice climbing practice tool showing my new design;

FIG. 2 is an upperfront perspective view thereof;

FIG. 3 is a left side elevational view thereof, the right side being a mirror image;

FIG. 4 is a front elevational view thereof;

FIG. 5 is a rear elevational view thereof;

FIG. 6 is a bottom plan view thereof; and,

FIG. 7 is a top plan view thereof.

The shade lines in the FIGURES show contour and not surface ornamentation.
